[57] **CLAIM**

The ornamental design for a buggy wrap, as shown and described.

DESCRIPTION

FIG. 1 is a front elevational view of the buggy wrap showing my new design and the cross-hatching represents fabric and is understood to extend uniformly throughout the surface;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The four square shaped areas in FIG. 1 and the four rectangular shaped areas in FIG. 2 represent hook and loop fastening material.

FIG. 1

FIG. 2

FIG. 3

FIG. 4

FIG. 5

FIG. 6
